United States Patent Office

Des. 211,232
Patented June 4, 1968

211,232

PANTY GIRDLE

Louise M. Tenuziak, Lincoln Park, N.J., assignor to Sarong, Inc., Dover Del., a corporation of Delaware

Filed Nov. 10, 1966, Ser. No. 4,611

Term of patent 14 years

(Cl. D2—4)

Fig. 1 - 1

FIGURE 1

I claim:

The ornamental design for a panty girdle, as shown.
